Primary Examiner — Cynthia R Underwood

(74) *Attorney, Agent, or Firm* — Taylor J. Ross

(57) **CLAIM**

The ornamental design for a serving dish, as shown and described.

DESCRIPTION

FIG. 1 is a top, front and left side isometric view of a first embodiment of a serving dish showing our new design;

FIG. 2 is a bottom, front and right side isometric view thereof;

FIG. 3 is a top plan view thereof;

FIG. 4 is a bottom plan view thereof;

FIG. 5 is a front elevation view, the rear elevation being a mirror image thereof;

FIG. 6 is a left side elevation view thereof;

FIG. 7 is a right side elevation view thereof;

FIG. 8 is a cross-sectional view taken along line 8-8 of FIG. 3;

FIG. 9 is a cross-sectional view taken along line 9-9 of FIG. 3;

FIG. 10 is a top, front and left side isometric view of a second embodiment of a serving dish showing our new design;

FIG. 11 is a bottom, front and right side isometric view thereof;

FIG. 12 is a top plan view thereof;

FIG. 13 is a bottom plan view thereof;

FIG. 14 is a front elevation view, the rear elevation being a mirror image thereof;

FIG. 15 is a left side elevation view thereof;

FIG. 16 is a right side elevation view thereof;

FIG. 17 is a cross-sectional view taken along line 17-17 of FIG. 12;

FIG. 18 is a cross-sectional view taken along line 18-18 of FIG. 12;

FIG. 19 is a top, front and left side isometric view of a third embodiment of a serving dish showing our new design;

FIG. 20 is a bottom, front and right side isometric view thereof;

FIG. 21 is a front elevation view, the rear elevation being a mirror image thereof;

FIG. 22 is a left side elevation view thereof;

FIG. 23 is a right side elevation view thereof;

FIG. 24 is a top plan view thereof;

FIG. 25 is a bottom plan view thereof;

FIG. 26 is a cross-sectional view taken along line 26-26 of FIG. 24; and,

FIG. 27 is a cross-sectional view taken along line 27-27 of FIG. 24.
